UNITED STATES PATENT OFFICE.

JOHN W. EISENHUTH, OF BROOKLYN, NEW YORK, ASSIGNOR, BY MESNE ASSIGNMENTS, TO THE COMPOUND MOTOR COMPANY, A CORPORATION OF WEST VIRGINIA.

GAS-ENGINE.

No. 838,018.

Specification of Letters Patent.

Patented Dec. 11, 1906.

Application filed March 23, 1905. Serial No. 251,679.

To all whom it may concern:

Be it known that I, JOHN W. EISENHUTH, a citizen of the United States, residing at Brooklyn, in the county of Kings and State 5 of New York, have invented certain new and useful Improvements in Gas-Engines, (Case B;) and I do hereby declare the following to be a full, clear, and exact description of the invention, such as will enable others skilled 10 in the art to which it appertains to make and use the same.

This invention relates to improvements in gas-engines, and particularly to compound gas-engines in which high-pressure cylinders 15 and low-pressure cylinders operated by the exhaust from the high-pressure cylinders are employed.

It is the purpose of the invention to provide such an engine, so arranging the high-pressure cylinders that a double-acting low-pressure cylinder may be employed and a common crank-shaft may be used for receiving power from the pitmen of all the cylinders.

25 The invention comprises certain novel constructions, combinations, and arrangements of parts, as will be hereinafter fully described and claimed.

In the accompanying drawings, Figure 1 is 30 a horizontal sectional view through a gas-engine, the section being taken through the cylinders of the engine and through the valve casings and portions of the framing being broken away to show the crank-shaft and some of the connecting parts. Fig. 2 is a 35 view, partially in side elevation and partially in vertical section, showing the arrangement of the high and low pressure cylinders and the connection of their pistons with a common crank-shaft. Fig. 3 is a vertical central transverse section of the machine, the framing of the machine being partially broken away and parts of the high-pressure cylinders being shown in section to the rear 40 of the low-pressure cylinder. Fig. 4 is a top plan view of a similar engine provided with horizontally-arranged high-pressure cylinders and a vertically-arranged low-pressure cylinder, portions of the engine being broken away to better show the parts. Fig. 5 is a 45 side elevation of the same. Fig. 6 is a detail view showing one of the valves for controlling the inlet of explosive charges to the high-pressure cylinders and for admitting the ex-

haust from the said high-pressure cylinder to 55 the low-pressure cylinder.

The present invention involves the employment of a plurality of high-pressure cylinders and a low-pressure cylinder which is capable of receiving the exhaust-gases from 60 the high-pressure cylinder and utilizing them for driving a piston of large area.

I have shown in the drawings a preferred form of engine in which, as shown in Figs. 1, 2, and 3, four upright high-pressure cylinders 65 1 are arranged adjacent to a low-pressure cylinder 2. For the sake of producing a compact mechanism the high-pressure cylinders are preferably grouped about the low-pressure cylinder and are arranged opposite 70 to each other in pairs, so that the pitmen of the high-pressure pistons may extend to the same cranks upon the shaft of the engine. The high-pressure cylinders are preferably open at one end, so that explosive charges 75 are applied to one side of the pistons, which high-pressure cylinder operates, therefore, as a four-cycle engine, one movement being employed to draw in the explosive charge of gaseous material, the return stroke being employed to compress the mixture for ignition after which the piston is driven back again by the explosion resulting, and upon the return the exhaust-gases are forced into the low-pressure cylinder and a new charge is 80 drawn into the engine. Pistons 3 are provided in each of the high-pressure cylinders and are connected by means of pitmen 4 and 5 with a crank upon the engine-shaft 6, which is arranged directly opposite thereto. 85 Thus one set of pitmen 4 and 5 are connected with the crank 7, while the other set are connected with a crank 8. In order that the pitmen 4 and 5 of oppositely-arranged high-pressure cylinders may approach and 90 properly engage the same crank, one of said pitmen is bifurcated at its lower end, as indicated at 9, while the other pitman extends between the ends of the bifurcated portions. The single and bifurcated ends of these meeting pitmen are provided with bearings 95 which engage the bearing portions of the cranks 7 and 8. The ends of the high-pressure cylinders which hold the explosive gases and which form the exploding-chambers 100 thereof are preferably provided with cooling means—such, for instance, as water-jackets 105 10, illustrated in the drawings.

In order to economize space and make a more compact structure, the high-pressure cylinders are preferably grouped about a single low-pressure cylinder, as 2, which is arranged in the middle. When using four high-pressure cylinders, I employ a double-acting low-pressure cylinder provided with a trunk-piston 11, which is capable of actuation in both directions, pressure being applied alternately to one side and then to the other. The cylinder 2 is closed at both ends by cylinder-heads 12 and 13. The head 13 is formed with a central opening, and an elongated bearing 14 is formed therein, the walls of said bearing extending some little distance within the cylinder as well as partly outside the same. The piston 11 is formed with an annular recess 15 upon the side thereof of which is adjacent to the bearing 14. The said recess receives the inner edge of the bearing 14 when the piston is in the lower part of the cylinder. By this construction the piston can be made of sufficient depth to secure a good bearing upon the inner surface of the cylinder 2 and can be provided with a sufficient number of packing-rings to secure a tight joint between the said piston and the walls of the cylinder. The central portion of the piston 11 is hollow and tubular, as at 16, the tubular stem thus formed upon the piston fitting snugly in the bearing 14 and reciprocating therein. A pitman 17 extends into the tubular stem or barrel of the piston and is pivotally connected thereto, as at 18. The outer end of the pitman 17 is connected with a crank 19 formed upon the shaft 6.

The structure above described, whereby the piston-head is made of considerable length and is provided with considerable bearing-surface engaging the walls of the cylinder, is of advantage also in that it makes it possible to properly control the exhaust from the said low-pressure cylinder. In order to accommodate the exhaust, a centrally-arranged outlet-port 20 is formed in the walls of the cylinder 2, and this port is only uncovered when the piston 11 is at the extremes of its movement. It will thus be evident that when pressure is introduced into one end of the cylinder it will be retained within the cylinder and operate against the piston until it has driven the piston sufficiently close to the other end of the cylinder to uncover the port 20. Upon the uncovering of said port the exhaust will immediately find its way out of cylinder. As soon as the piston is driven by a new charge to the other end of the cylinder, the new charge being placed upon the opposite side of the piston from the first charge, the exhaust-port will again be uncovered, and a second charge will be permitted to exhaust. In this simple manner the exhaust can be controlled and permitted through the action of the piston within the low-pressure cylinder.

The piston 11 is preferably made hollow, and the space within it is connected with the casings of the engine through the hollow stem or barrel portion thereof.

The engine-shaft 6, together with the cranks, pitmen, and lower ends of the cylinders, may be embraced within a closing casting, as 21, for excluding dust and foreign substances and also for permitting of the running of the parts in oil, if desired.

Operating in conjunction with the moving shaft and the reciprocating pistons of the high and low pressure cylinders are valves for controlling the admission and passage of gaseous mixtures and exhaust products through and from the engine. While I may employ any desired type of valves, I preferably use valves such as are shown in the drawings, and particularly in Figs. 1 and 6, which are of the revoluble type. Said valves are formed with hollow cylindrical heads 22, which fit snugly in casings 23, within which they may be turned or regulated. Actuating stems or valve-rods 34 are connected with the said heads and project outwardly from the casings thereof to a point in suitable proximity to the working parts of the engine to receive motion therefrom. A simple manner of transmitting movement to the valves is illustrated in the drawings, the said valve-stems 34 carrying beveled gears 35, which mesh with beveled pinions 36, secured to the shafts 37, which are arranged counter to the engine-shaft 6. The counter-shafts 37 are driven by means of gearing which receives motion from the engine-shaft 6, such gearing usually consisting in a driving-pinion 38, secured to the shaft 6 and meshing with intermediate gears 39, which in turn mesh with larger gears 40, secured to the counter-shafts 37. Since there are two valves arranged upon each side of the engine and two counter-shafts 37 are employed, it is needful that two sets of gears 40 be provided, one gear for each shaft, and two intermediate pinions 39 interposed between the same and a single driving-pinion 38, carried by the engine-shaft 6. The valves are so constructed that when they are turned to one point in a rotating or oscillatory movement they will admit of charges of gaseous material being drawn into the high-pressure cylinders of the engine. Such charges of gaseous material are delivered to the engine through pipes 41, which connect with branch pipes 42, leading to each of the adjacent high-pressure cylinders. The walls of the casings which surround the valves are provided with ports, some of which are opposite the inlet-pipes 42, as shown at 43, while other ports, as 44, lead from the casings into the high-pressure cylinder, and again a third set of ports 45 communicate with piping 46, which leads to the ends of the low-pressure cylinder.

The valves in order to properly perform

their functions are made hollow, as shown in Figs. 1 and 6, and are provided with diametrically-arranged partitions 47, which divide the valves into two chambers. Ports 48 and 49 are formed in the walls of said valves, so as to communicate with the chambers upon the opposite sides of the partition 47. When a valve is turned in one position, a port 48 will cover the inlet-port 43 and the cylinder-port 44, and a charge of gaseous mixture may then pass through the valve mechanism into said cylinder. When the valve is turned to another position, the port 48 will no longer connect the ports 43 and 44, and the port 49 will thus connect the ports 44 and 45, so that as the cylinder exhausts the exhaust-gases will be led into one end of the low-pressure cylinder. The valves opposite high-pressure cylinders 1 are arranged to act alternately, so that when one cylinder is being acted upon by an exploding charge of gases the cylinder opposite to it will be exhausting into one end of the low-pressure cylinder. On the other side of the engine the same thing will occur, but in reverse order, and the exhaust from the high-pressure cylinders upon that side of the engine will be led into the opposite end of the low-pressure cylinder from that which receives the exhaust on the other side of the engine. By this simple construction it will be evident that two of the high-pressure cylinders upon opposite sides of the machine are alternately operated by explosive charges while the other two are exhausting into the low-pressure cylinders.

The high-pressure cylinders of course are provided with suitable spark-producing devices, as 50, which are mounted in their upper ends and connected with any suitable source of electricity.

While the high-pressure cylinders may be arranged at an angle with respect to each other and with respect to the low-pressure cylinder, as indicated in Figs. 1 and 2, the said high-pressure cylinders may have to be arranged horizontally, as shown in Fig. 4, with the low-pressure cylinder rising from the middle of the machine, as clearly seen in Fig. 5. In this instance the opposite high-pressure cylinders are arranged upon the same line as an axis, and their pitmen 51 and 52 project toward each other and engage the same crank 53 upon the engine-shaft. In an engine of this structure the outer ends of the high-pressure cylinders receive the explosive charges and are provided with water-jackets, as 54, and hold the igniters 55. The gaseous material is conducted to the engine by means of pipes 56, which lead to branch pipes 57, connecting with valve-casings 58. Valves in these casings are operable for admitting the gaseous mixtures at the proper time into the adjacent cylinders. The valve-casings also are provided with valves, as at 59, which control the passage of the exhaust-

gases from the high-pressure cylinder through piping 60 to the low-pressure cylinder 61. Two of the oppositely-arranged high-pressure cylinders communicate with the lower end of the low-pressure cylinder, as shown in Fig. 5, while the other two communicate with the upper end of said cylinder. The low-pressure cylinder 61 is constructed like the cylinder 2, and a double-acting piston is mounted therein. The cylinder 61 is also provided with a centrally-arranged exhaust exit or port 62, similar to the port 20 in the cylinder 2. The exhaust is thus controlled in its outlet by the movement of the piston within the low-pressure cylinder, as above described with respect to the piston 11. The valves employed in the form of engine shown in Figs. 4 and 5 may be of the same type as that heretofore described or may be puppet-valves, as indicated at 63, the stems 64 of which extend outside the casing and engage cams 65, carried by the shaft 66. The shaft 66 extends at right angles to the shaft of the engine and is provided with a worm-gear 67, which meshes with a corresponding worm 68, carried by the engine-shaft. In this way the valve-operating cams are properly operated in timed relation to the movement of the engine-shaft and the pistons in the cylinder of the engine. In this form of engine it is preferable to employ a check-valve, as at 69, where branch pipes lead into the low-pressure cylinder from oppositely-arranged high-pressure cylinders, the said valve preventing the possibility of back pressure in one cylinder while the other is in the act of receiving an explosion. It will be evident that the type of engine shown in Figs. 4 and 5 will be admirably adapted for use where it is desired to keep the weight of the engine as low as possible. For this reason such an engine would be suitable for marine uses and the like.

It will be evident that the minor details of construction in the engine and the exact arrangement of the cylinders may be somewhat altered without departing from the spirit of the invention.

It will be evident from the above description that a very powerful rotary movement may be imparted to the engine-shaft by the employment of a group of high-pressure cylinders having an opposite or balanced relation to the shaft of the engine and a low-pressure cylinder also properly connected with the shaft and that the gaseous mixtures introduced into the engine may be not only exploded in the high-pressure cylinders for use, but may lead in their exhausting condition into the low-pressure cylinder for further utilizing their explosive powers.

Having thus fully described my invention, what I claim as new, and desire to secure by Letters Patent, is—

1. A compound gas-engine, comprising a

plurality of high-pressure cylinders, two of said high-pressure cylinders being arranged opposite each other to form pairs and a low-pressure cylinder of greater diameter arranged between pairs of high-pressure cylinders, one pair of high-pressure cylinders being connected with one end of the low-pressure cylinder while the other pair of high-pressure cylinders is connected with the other end of the low-pressure cylinder, the low-pressure cylinder thus being operated by the exhausts from the pairs of high-pressure cylinders, pistons moving in all of said cylinders and a crank-shaft connected with all of said pistons.

2. A compound gas-engine, comprising a plurality of high-pressure cylinders arranged for receiving explosive charges at one end, a low-pressure cylinder arranged between the high-pressure cylinders and arranged for receiving exhaust charges from the high-pressure cylinders at each end, a trunk-piston mounted in the low-pressure cylinder having a pressure-receiving surface arranged upon both ends thereof, a crank-shaft extending opposite the ends of all of the cylinders, pistons moving in the high-pressure cylinders, and pitmen connecting all of the pistons with the crank-shaft for imparting movement thereto.

3. A compound gas-engine, comprising a plurality of high-pressure cylinders, arranged at an angle to each other in pairs, pistons moving in said high-pressure cylinders, a crank-shaft in alignment with the axes of the cylinders, pitmen connecting the pistons of the high-pressure cylinders with the crank-shaft, a low-pressure cylinder arranged adjacent to the high-pressure cylinders, means for connecting both ends of the low-pressure cylinder with the exhaust-outlets of the high-pressure cylinders, a double-acting piston mounted in the low-pressure cylinder and a pitman connecting the same with the said crank-shaft.

4. A compound gas-engine, comprising a plurality of high-pressure cylinders open at one end, a low-pressure cylinder mounted adjacent thereto and closed at both ends, the head at one end of the cylinder being provided with a central elongated bearing, the bearing extending into the low-pressure cylinder a considerable distance, a piston moving in the cylinder and provided with an annular recess on one face for fitting around the said elongated bearing, a tubular projection formed upon the piston and projecting into the said bearing, an engine-shaft mounted in alignment with the axes of all of said pistons and pitmen connecting the pistons of the cylinders with the said shaft.

5. A compound gas-engine, comprising

high and low pressure cylinders, the low-pressure cylinder being provided with heads for closing its ends, the head at one end having an elongated tubular bearing formed therein and extending into the cylinder, and a piston moving in the low-pressure cylinder and formed with a hollow tubular extension engaging the said elongated bearing of the cylinder-head, the said piston being also provided with an annular recess for receiving the inner end of the said bearing and permitting of a full-length stroke of the piston within the cylinder, an engine-shaft suitably mounted in alignment with the cylinders, and a pitman pivotally mounted within the hollow extension of the low-pressure piston and connected with the engine-shaft.

6. A compound gas-engine, comprising approximately upright high-pressure cylinders and an upright low-pressure cylinder of larger diameter than the high-pressure cylinders, the high-pressure cylinders being arranged around the low-pressure cylinder, an engine-shaft extending opposite the ends and in alignment with the axes of the said cylinders and formed with a crank opposite each cylinder, pistons moving in all of said cylinders, pitmen connecting the pistons with the cranks opposite their respective cylinders, means for introducing explosive charges into the ends of the high-pressure cylinders, means for directing the exhaust-gases from the high-pressure cylinders into the ends of the low-pressure cylinder, and means for permitting of a final escape of the exhaust-gases from the low-pressure cylinder.

7. A compound gas-engine, comprising a centrally-mounted vertical low-pressure cylinder, high-pressure cylinders arranged in pairs upon each side thereof and reversely inclined with respect to the axis of the low-pressure cylinder, the said high-pressure cylinders converging toward the engine-shaft, an engine crank-shaft mounted adjacent to the ends of the cylinders, pistons moving in all of said cylinders, cranks formed upon the crank-shaft respectively opposite the pairs of high-pressure cylinders and the low-pressure cylinder, the pitmen of each pair of high-pressure cylinders being connected with the same crank, and valves controlling alternately the inlet of explosive charges to the high-pressure cylinders and the passage of exhaust charges to the low-pressure cylinder.

In testimony whereof I affix my signature in presence of two witnesses.

JOHN W. EISENHUTH.
